UNITED STATES PATENT OFFICE.

JUDSON L. THOMSON, OF SYRACUSE, NEW YORK, ASSIGNOR OF ONE-HALF
TO C. VALLETTE KASSON, OF DETROIT, MICHIGAN.

PANTALOON-PROTECTOR.

SPECIFICATION forming part of Letters Patent No. 258,155, dated May 16, 1882.

Application filed February 9, 1882. (No model.)

To all whom it may concern:

Be it known that I, JUDSON L. THOMSON, of Syracuse, in the county of Onondaga, in the State of New York, have invented new and useful Improvements in Pantaloons-Protectors, of which the following, taken in connection with the accompanying drawings, is a full, clear, and exact description.

This invention relates to a novel construction of a pantaloons-protector adapted to be readily secured to the heel of a boot or shoe, and supporting the base of the pantaloons-legs, so as to protect the same from being soiled.

The invention is fully illustrated in the annexed drawings, wherein Figures 1 and 2 are side and face views, respectively, of my improved pantaloons-protector as applied to the heel of a boot, and Fig. 3 is a top view of the same detached.

Like letters of reference represent like parts in all the figures.

a denotes the attaching-plate of the pantaloons-protector, said plate being of such a shape as to properly fit the back part of the heel. The upper edge of the plate *a* is provided with hooks or spurs *n* *n*, adapted to engage the heel at its junction with the counter of the boot or shoe, as shown in Fig. 1 of the drawings. The lower portion of the plate *a* is provided with a hole, through which the attaching-screw *u* passes, said screw entering the heel and firmly securing thereto the aforesaid plate. Between the spurs *n* *n* the upper portion of

the plate *a* is bent into a loop, *b*, on which is hinged the arm or bail, *d*. The ends of the loop have two notches, *c* *c*, one of which is in such relative position as to arrest the movement of the bail *d* when in a horizontal position, as shown in Fig. 1 of the drawings, and cause said arm to spring back into said position in case it is unduly depressed. The other notch, *c*, is on top of the end of the loop, and serves to retain the bail *d* when turned up and out of the way, as illustrated in Fig. 2 of the drawings, the bail having sufficient spring to allow it to be swung from notch to notch and adjusted in its desired position.

Having described my invention, what I claim is—

The within-described pantaloons-protector, consisting of the plate *a*, provided with the spurs *n*, and with the loop *b*, having the notches *c* *c*, the bail *d*, hinged in said loop, and the attaching-screw *u*, inserted through the lower portion of the plate, substantially as described and shown.

In testimony whereof I have hereunto signed my name and affixed my seal, in the presence of two attesting witnesses, at Syracuse, in the county of Onondaga, in the State of New York, this 26th day of January, 1882.

JUDSON L. THOMSON. [L. S.]
